UNITED STATES PATENT OFFICE.

GEORGE HOFMANN AND ROBERT G. SCHROEDER, OF CHICAGO, ILLINOIS, ASSIGNEES
TO RALPH A. BARD, TRUSTEE, OF CHICAGO, ILLINOIS.

COMBINED WRITING INSTRUMENT.

Application filed February 2, 1922. Serial No. 533,676.

To all whom it may concern:

Be it known that we, GEORGE HOFMANN and ROBERT G. SCHROEDER, citizens of the United States, residing at Chicago, in the county of Cook and State of Illinois, have invented certain new and useful Improvements in Combined Writing Instruments, of which the following is a specification.

Our invention has for its general object to provide, in a combined writing instrument, a fountain pen, lead-feeding pencil and lead-magazine, all in simple, inexpensive and efficient construction and cooperation. Among the desiderata of our invention are to provide such construction of the elemental parts of the combined instruments—the fountain pen, pen-cap, and pencil—that, in a single combined instrument of relatively short length, consistent with the limitation which public demand places on a pocket-carried writing instrument, there may be provided a pen element of satisfactory ink-carrying capacity, a pencil element using lead of satisfactory unit-length, and a fountain pen-cap serving as a lead reservoir or carrier, and all in an instrument that will satisfy reasonable demands as to balance, ease of manipulation and satisfactory appearance.

For the attainment of these objects, and others which will become apparent from the following description, our invention consists in the combinations of elements and features of construction hereinafter set forth and claimed, and in the drawings we have illustrated for purposes of disclosure a single embodiment of our invention in its preferred form of construction, some of the details of which we may claim for their specific advantages, although it will be apparent that in the broader aspects of our invention many changes in detail may be made without departure from the spirit of the invention and within the scope of the claims.

In said drawings Fig. 1 is a side elevation of the writing instrument with parts broken away and showing, in dotted lines, the position of the cap when the pen is in use. Fig. 2 is an enlarged central vertical section through the pencil assembly; Fig. 3 is a longitudinal section of the screw-shell and turning-sleeve sub-assembly; Fig. 4 is a detail of the propelling nut member with the nut-rim and a nut-supporting arm in section; Fig. 5 is a section on line 5—5 of

Fig. 4; Fig. 6 is a section, with fragments in elevation, of the tip and tube assembly; Fig. 7 is a section on line 7—7 of Fig. 6; Fig. 8 is an enlarged longitudinal section of the lead-magazine-cap, and Fig. 9 is a section on line 9—9 of Fig. 8.

The fountain pen 10 may be of suitable self-filling type, typified by the presence of the filling bag 11 and is provided with a cap 12 constructed for coaction with the end 65 carrying the pen-point 13 or the end equipped with the pencil mechanism 14. The pencil mechanism is made very short in proportion to the length of lead handled by it, and preferably is seated within the tubular pen barrel 15 only sufficiently for requisite strength of the joint, so that the bag 11 for carrying the ink of the fountain pen may be of adequate capacity. In the pencil mechanism the tip shell 16 may turn with a 70 knurled operating ring 17 to which, preferably, it is detachably connected, and the tip shell carries with it in rotation the feed tube 18 aligning with the orifice 19 of the tip. As shown in Fig. 6, 75 the tube may be rigidly seated or soldered in the smaller end of the generally conical tip shell, the larger end of which has force-fitted into it an internally threaded ring 20, reinforcing it and providing means for its 80 detachable association with the threaded boss of the knurled turning ring 17. Rigidly positioned in the barrel element 15 is the internally threaded screw-sleeve 21, with the threads of which there coacts a nut 22, the 85 body of which enters the feed tube 18 and makes slidably, but non-rotatable engagement therewith, the portion of the body within the feed tube carrying a lead-feeding pin 23 to coact with the end of the lead 24. 90 Specifically, the feed-tube 18 has diametrically opposed slots 25 in its sides, running from the rear end of the tube for approximately lead-length, and the nut structure 22 is formed to provide a rim 26 completely 95 encircling the tube, externally threaded as at 27 and preferably of sufficient length to take at least one full thread-turn. Thin diametrically opposed arms 28, to fit in the slots 25, connect the rim 26 with the body- 100 pin 23, and in manufacture the rim may be made independently of the body and arms, the arms forced into rigid engagement with the annular rim. By thus encompassing the wall of the split tube with the rim com- 105 110

pletely surrounding it the tube is reenforced so that it may withstand a very considerable torsionable strain without bending. Of course, as the tip-carried feed tube is rotated, turning the nut with it, the nut progresses longitudinally of the tube by virtue of its threaded engagement with the relatively stationary screw-sleeve 21 and advances the lead through the tension-spring 10 29 of the tip-structure.

For securing the screw-sleeve 21 in the barrel 15, and mounting the turning ring 17 for free rotation, yet so that it may be securely positioned, I preferably connect the 15 turning ring 17 with the tube-positioning structure in a manufacturing sub-assembly. Thus, as shown in Fig. 3, I form up a retaining thimble 30 with its cylinder wall 31 flanged at its upper end at 32 adapted to 20 be cemented in the end of the pen barrel and with its bottom wall 33 provided with a re-entrant flange 34 to form an annular seat, the inner margin of said flange being upset to retain the washer 35 between which 25 washer and the walls of the thimble the sleeve member 37 of turning ring 17 engages for free rotation. This turning member may in turn be made in two pieces for manufacturing facility, the threaded collar 30 portion 17^a being rigidly fitted into the knurled head portion 38 of sleeve 37, and the rear end of the sleeve being inwardly flanged as at 39 so as to be retained under the washer 35. The nut member 22, when 35 screwed into the screw barrel 21 may be retained against accidental displacement by retaining rings 40, 40' sprung into the extremities of the barrel.

The operation of the construction will be 40 apparent. The nut assembly shown in Fig. 4 is placed in the screw barrel of the sub-assembly shown in Fig. 3 and the retaining ring 40 is applied. The parts thus assembled are placed in the fountain pen barrel 45 with the thimble 30 cemented or otherwise retained. A lead is inserted in the feed tube and then the tube is slipped into the screw barrel 21 and its split sides caused to pass between the arms 28 of the nut. The tip is 50 then screwed home on the threaded collar 17^a of the turning piece 17, and thereafter, as the turning piece is rotated in proper direction, carrying with it the tip and feed tube, the nut is caused to progress along 55 the threads of the screw-barrel, advancing the lead.

The cap 12 is formed with its open end or mouth engageable with either end of the pencil, and the normally-closed end of the 60 cap is formed as a magazine for extra lead. In the specific construction shown a shoulder 43 is internally formed in the cap at a point beyond the range of possible interference with the pen point or the pencil tip and an 65 inner sleeve, preferably of rubber is inserted

beyond the shoulder to leave a lead-receptive space between the sleeve and the cap wall, such space being preferably divided into compartments by ribs 45 on the exterior of the sleeve, as best shown in Fig. 9. The sleeve-length should be slightly greater than that of a replacement lead and in the open end of the sleeve a collar 47 is inserted, having a flange 48 partly to overlie the lead-receptive spaces. An eraser 49 is preferably 75 carried in this flanged collar, and overlying the eraser we provide a slip-fitted metal cap 50, removable to expose the rubber. Holding clip, 51, may be provided as a ball-ended spring 52, the narrow end of which is passed, as at 54, through an aperture in the cap and then extends, as at 55, along the inside 80 of the cap in a groove 56 formed to receive it in one of the ribs 45 of the magazine-sleeve.

It will thus be apparent that by special cooperative construction of pen, pencil and cap elements, we provide a combined writing instrument having but little more length than a fountain pen alone of similar ink-holding capacity, and yet including a mechanical pencil capacitated to receive a lead of satisfactory length, and all with provision for the carriage in a convenient magazine of a large supply of renewal lead.

While we have herein shown and described a single embodiment of our invention in simple, compact form particularly designed for operative excellence and manufacturing economy, it will be apparent that changes in details of construction may be made without departure from the spirit of our invention within the scope of the appended claims.

We claim:

1. In a writing instrument of the character described, the combination with an open-ended shell, of a thimble shallowly seated in said shell and relatively fixed therein, a non-rotatable feed member fixed to the inner or bottom end of said thimble, a rotatable feed member coacting with said non-rotatable feed member, one said feed member having a longitudinal slot and the other said feed member having screw thread provision, a feed nut engaging the slotted and screw-threaded feed members for movement along the relatively stationary feed member as the rotatable feed member is rotated, and a turning member, exteriorly accessible beyond the forward end of said thimble, said turning member entering said thimble for guidance therein and having provision for engagement with the rotatable feed member.

2. In a writing instrument of the character described, the combination with an open-ended barrel, of a thimble shallowly seated in and fixed to said barrel; a rotatable structure seated in said thimble and extending a major portion of the interior length thereof,

- 5 said rotatable structure comprising a turning member externally accessible beyond the outer end of said thimble and normally retained against axial displacement in the thimble and comprising also a tip-member detachably connected with said turning member, and feed mechanism comprising a non-rotatable structure mounted in the bottom or inner end of said thimble and a 10 relatively rotatable feed member engaging the rotatable structure aforesaid, one of said feed members being longitudinally slotted and the other having screw-thread provision, and a feed nut engaging both the 15 thread and the slot for axial displacement as said turning member is rotated in the thimble.
3. The combination with a fountain pen barrel open at its end, of mechanical pencil mechanism shallowly seated therein comprising a rotatable structure including a portion entering the barrel end for support and a tip structure detachably carried by said portion; feed mechanism comprising a 20 member connected with said rotatable structure for rotation therewith, a non-rotatable member and a feeding nut, one of said members being longitudinally slotted and the other having screw thread provision, both 25 the slot and the screw thread being engaged by the nut; and means, including a shallow thimble that surrounds the feed mechanism and engages the barrel adjacent to the open end of the latter, connecting the inner end of 30 the non-rotatable member with the barrel.
4. In a device of the character described, the combination with a shell (15) of a screw sleeve relatively fixed therein, a turning 35
- member (17) rotatable with respect to said sleeve in longitudinally fixed position, a feed-tube member detachably connected with said turning member for rotation therewith and carrying a nut, in rotation therewith, and said nut, slidably longitudinally of the feed-tube and making threaded engagement 40 with the screw sleeve.
5. In a pencil of the character described, the combination with a shell (15) open at its end, of a thimble shallowly seated in said shell and relatively fixed therein, a fixed 45 screw-sleeve carried by said thimble, a lead-feeding nut engaging said screw sleeve, a lead-feeding tube slidably but non-rotatably engaging said nut, and a rotatable structure 50 at one end fixedly engaging the feed-tube and at its other end rotatably engaging in said thimble.
6. In a pencil of the character described, the combination with a shell (15) open at its ends, of a thimble shallowly seated in 55 said shell and relatively fixed therein, a fixed screw-sleeve carried by said thimble, a lead-feeding nut engaging said screw-sleeve, a lead-feeding tube slidably but non-rotatably 60 engaging said nut, and a rotatable structure at one end fixedly engaging the feed-tube and at its other end rotatably engaging in 65 said thimble, said rotatable structure comprising two separable sections, whereof that section rotatably engaging the thimble is 70 retained therein against axial displacement and the feed-tube-carrying section is axially removable.
